UNITED STATES PATENT OFFICE.

HENRY WITTE, OF NEW YORK, N. Y., ASSIGNOR TO GUERIN-POUYAT-ELITE, LTD., OF NEW YORK, N. Y., A CORPORATION OF CANADA.

DESIGN FOR A COVERED DISH.

Application filed December 9, 1926. Serial No. 19,992. Term of patent 7 years.

To all whom it may concern:

Be it known that I, HENRY WITTE, a citizen of the United States, and resident of the borough of Manhattan, in the city and State of New York, have invented a new, original, and ornamental Design for a Covered Dish, reference being had to the accompanying drawing, forming a part thereof.

Fig. 1 represents a top plan view of the covered dish, showing my new design.

Fig. 2 represents a side view of the same.

I claim:—

The ornamental design for a covered dish substantially as shown.

HENRY WITTE.
